UNITED STATES PATENT OFFICE.

JAMES J. CASEY, OF BOSTON, MASSACHUSETTS; KATHERINE F. CASEY, ADMINISTRATRIX OF SAID JAMES J. CASEY, DECEASED, ASSIGNOR OF ONE-HALF TO GARDNER W. PEARSON, OF LOWELL, MASSACHUSETTS.

MARKING-MACHINE.

1,324,877.

Specification of Letters Patent. Patented Dec. 16, 1919.

Application filed December 18, 1915. Serial No. 67,604.

To all whom it may concern:

Be it known that I, JAMES J. CASEY, a citizen of the United States, residing at Boston, in the county of Suffolk and State of Massachusetts, have invented certain new and useful Improvements in Marking-Machines, of which the following is a specification.

This invention relates to devices for marking the position of buttons, button holes or of both on sheet material such as leather or cloth.

It is more particularly intended for marking the location of buttons and button holes on the uppers of shoes in the process of manufacture thereof. It may be used for marking the location of the buttons on the button fly, or of the button holes on the button hole fly or it may be used for marking both at the same time in the manner indicated by application for patent filed by me on process for marking shoe uppers July 17, 1913, Ser. No. 779,504 and application for patent filed by me on marking machine for shoe uppers filed Dec. 19, 1913, Ser. No. 807,691 issued May 16, 1916, No. 1,183,432.

With my device, I use a plurality of spaced marking members, such members being preferably awls, arranged on a curved line.

The principal purpose of my invention is to provide suitable means for positioning and for changing the longitudinal spacing of the marking members on a curved line and to provide means of such a character that when the shape of the curve is changed, the spacing means may still be so operated as to simultaneously adjust the distances between all or substantially all of the marking members.

To accomplish my purpose, I use a plurality of fingers each pivoted near one end to supporting means which may be a rigid frame, a plurality of carriers, a strip, or a flexible strip, each of such fingers having a marking member near its other or free end. In connection therewith, I use position determining means which may consist conveniently of a handle integral with one of the pivoted fingers or a set screw carried by the frame. I use to connect the fingers with each other, with the position determining means, or with both, a plurality of links

in different relations therewith. These links may pivotally connect adjacent or non-adjacent fingers at irregular distances from the pivotal points of the fingers on the supporting means, or some or all may be pivoted near one end at different distances from the pivotal points of the fingers on the supporting means and near their other ends at a single point on another link or on the position determining means, or on a line at right angles to its adjusting movement; or they may be pivoted near one end at unequal distances on a line at an angle to its adjusting movement on the position determining means and near their other ends at equal distances from the pivotal points of the fingers on the supporting means; or I may use a combination of these various methods of connection. The principle involved is to transform a movement of the position determining means through a certain distance, by means of irregularly pivoted spacing links, into a series of movements of different distances by the free ends of some or all of the pivoted fingers.

The means for altering the longitudinal adjustment is preferably independently operable from that for the lateral adjustment, if lateral adjustment is provided for. This longitudinal adjusting or spacing means preferably acts simultaneously upon all or substantially all of the marking members and increases or decreases the distances between them equally.

This invention differs from my application for patent on shoe marking machine filed December 18, 1915, Ser. No. 67,605, from the fact that in this application the essential features are the pivoted fingers carrying marking means together with a spacing link or links pivoted in different relations thereto, while in such other application such features are not essential.

The lateral adjustment or altering the curve need not be simultaneous for all parts thereof.

I prefer to embody my idea in a device which is removable from a punching machine and I preferably make it invertible so that the button locations of the right shoe may be marked by one face and of the left shoe by the other face.

In shoe marking machines, the relative

55 60 65 70 75

80 85

85

90 95

105

spacing between the buttons or button holes have been made adjustable and simultaneously adjustable, but I can, with my device in its preferred form, not only change 5 the spacing of the buttons but also the curve which they form. This curve differs for different styles of shoes and its length differs for different sizes.

For determining the shape of the curve to 10 conform to the styles of different shoes, I may use for supporting means a flexible or elastic strip member preferably made of metal as fully described and claimed in application executed and filed by me of even 15 date herewith.

I may, however, use for a supporting means a rigid frame on which my fingers are pivoted, or I may use other supporting means than said flexible strip for laterally 20 changing the curvature. My pivoted fingers move in a plane in which also lies the curve of the strip or of the pivots or both, and my marking members, such as awls, are vertically disposed with reference to such plane.

25 In the drawings Figure 1 is a plan view of one form of my device with the top plate removed. Fig. 2 is an elevation thereof as from the right of Fig. 1. Fig. 3 is a plan view of said device showing a different curve and with part of the top plate broken away. Fig. 4 is a sectional view of Fig. 3 on line 4—4. Fig. 5 is an elevation of a punching machine with which I prefer to use my device. Fig. 6 is a plan view of another 30 construction wherein my fingers are pivoted to a rigid frame or strip. Fig. 7 is a fragmentary plan view with most of the top plate broken away and other parts omitted for clearness of another modification wherein 35 in the frame is similar to that shown in Figs. 1, 2, 3, and 4, the fingers being pivoted to a flexible band but the links being pivoted to fingers in different relations. Fig. 8 is a section of Fig. 7 viewed from the left on line 8—8. Fig. 9 is a plan view of another 40 modification with most of the top plate broken away to show the interior construction, and Fig. 10 is a sectional view from the left on line 10—10 of Fig. 9.

50 A represents my device as a whole. In Figs. 1, 2, 3 and 4, the bottom plate is 20 and the top plate is 21. Both are preferably flat of curved contour and together with a rigid strip 22, which is also preferably curved, and separating bars 23 and 24 form the frame of my device. As so constructed, the inside or concave side is substantially open.

60 The marking means include a plurality of fingers 30 which are of such thickness at their pivot ends 31 and at their other ends 32 that they are slidable between the top and bottom plates in what is ordinarily a horizontal plane. Their ends 32 project 65 from the concave side of the frame and

carry at right angles marking means 33 which project at right angles or vertically therefrom. I prefer to arrange on each finger two awls oppositely disposed so that the device may be used either side up. 70

Each finger is preferably recessed as shown at 34 and near the end opposite the awls is cut away in such a groove 35 that two oppositely disposed pivotal points are formed. 75

Through these grooves and between the pivotal points, I pass a flexible curved strip 40 upon which the fingers will pivot. When the curve of this flexible strip is changed, the marking means which include the fingers 80 30 and awls 33 thus associated therewith will be moved thereby and will assume and follow the curve of such strip.

85 As a means for changing the curvature of the strip member, I provide carriers 41 slidable between the top and bottom plates and each grooved at 42 so as to have two oppositely disposed bearing points one on each side of strip 40. These carriers 41 are each bored and threaded to receive the screw 90 shank of a set screw 43 each of which passes through slot 45 in rigid strip 22 which is part of the frame. Each has an annular neck 44 which sets into a slot 45.

95 By turning these set screws 43, the carriers 41 are forced in or out carrying with them flexible strip 40 which moves the fingers pivoted thereon and the marking members carried by the fingers as shown in Fig. 3. 100

105 I may use, to get the proper spacing, disks 48 similar to carriers 41 and similarly grooved at 49 between the pivot ends of certain adjoining fingers 30, to keep them properly spaced.

110 I prefer to connect adjoining fingers 30 by means of links 50 which are shown as pivoted near their opposite ends to adjoining fingers, and I prefer that the opposite ends of some of said links should be at different 115 distances from the pivotal points of said adjoining fingers on flexible strip 40. If the links were pivoted at equal distances from such pivotal points, when one finger was moved on its pivot, all the others would 120 move the same distance, but by changing the pivotal distances, I am enabled to so arrange the longitudinal adjustment of the marking means that the distances between adjoining marking members can be simultaneously increased or decreased equally or unequally whether on a straight line or a curve. 125

130 In marking the position of buttons on shoes, the position of the lower button is usually taken as the fixed point. I therefore arrange so that the marking awl for this button shall be attached to the finger at one end, and I prefer to attach to the finger at the other end a handle such as 37 130

by which the spacing between the spaced marking means including the fingers, links and awls can be conveniently altered and positioned. So arranged, the distance moved by the awl associated with the finger which carries handle 37 will be the greatest distance and the distances moved by the other awls associated with the other fingers will be less successively down to the awl carried by the finger at the other end which will move a very small distance. By means of a pin 26 which may be passed through any one of the holes 27 in top plate 21 into a hole 38 in the finger to which handle 37 is attached, I can position the parts and lock them against longitudinal displacement.

To assist in taking up loose motion, I may connect certain fingers by tension springs such as 46 and 47.

This device A as a whole may be attached to or associated with any suitable form of punching machine B such as shown in Fig. 5 whereby it may be caused to move up and down in the process of puncturing or otherwise marking the sheet material upon which it is to be used. It may be attached to the plunger 101 of the punching machine by any suitable means preferably of such a character that it can be attached either side up and with the ends in either direction.

I prefer to fix the end blocks 23 and 24 somewhat in from the ends of the top and bottom plates thus leaving a channel at each end, and I prefer to arrange the plunger 101 with depending clamp members 102 and 103 from which projecting toward each other are tongues 104 and 105 each of a size to fit snugly into the channel at either end of device A, whichever side of A is uppermost. When slipped into place, they can be held there by means of set screws 106 which tighten the clamps 102 and 103.

In Fig. 6 I show a construction in which the supporting means consists of a strip or frame which is shown as curved in the general shape of a shoe button curve at 50 and has substantially parallel ends 51 and 52 bent in the same direction therefrom.

To this frame, preferably in slots 55, along the part 50 are pivoted fingers 53, each near one end, upon pivot pins 56. Near the other or free end each carries an awl 54 which is the marking means. Another awl 54 may be fixed near the end of stationary finger 51 if desired.

For position determining means I use a pivoted finger 53 at one end, together with a set screw 58 which passes through a bearing 59 pivoted on fixed finger 52 and connected by swivel 61 with a pivot 60 on said finger 53. The links 57 are shown irregularly pivoted to adjoining fingers 53. Therefore, by turning set screw 58 in and out, the finger 53 to which it is connected is moved

a certain distance and this motion is transmitted through the links to the other fingers so as to move the marking means 54 different distances.

In Fig. 7 I show a construction wherein 70 120 is the bottom plate, 121 the top plate, 142 a rigid supporting strip similar to 22, and 140 a substantially flat flexible strip from the top of which project a plurality of bosses 43 which serve as pivots for the 75 fingers 61, 62, 63, 64, 65, 66, 67 and 68.

The position determining means may be a handle 69 integral with finger 68, and I may provide a hole 77 in finger 68 into which a pin such as 26 may be passed through any 80 one of holes similar to those 27 in top plate 121.

The lateral adjustment of flexible strip 140 can be accomplished by set screws 43 which screw into suitable holes in carriers 41, both 85 of which are similar to those shown in Fig. 1.

The arrangement of spacing links may be as shown in 74, 75 and 76, one end of each of which is pivoted to points respectively on fingers 65, 66 or 67 which are equally distant from the pivotal points of said fingers 90 on strip 140. The other ends, however, are pivoted on finger 68 at different distances from its pivotal point on said strip. Spacing link 73 may connect fingers 64 and 65 in 95 any manner desired to give their awl ends the same movement or a different movement.

The spacing links 70, 71 and 72 are pivoted at the same point 79 on finger 64 but near their other end each is pivoted at points 100 on fingers 61, 62 and 63 respectively which are at different distances from the pivotal points of these fingers on strip 140.

It will be seen that the spacing links can be pivoted to adjoining fingers or to nonadjacent fingers and that they can be arranged in different relations thereto to accomplish the result desired.

In Figs. 9 and 10 I show a construction wherein 130 is the bottom plate and 131 the 110 top plate, 123 and 124 are end bars and 132 a rigid connecting bar all similar to the construction shown in Fig. 1. Instead of a flexible strip; however, I use a plurality of carriers 81 each of which is cut away at 82 115 to receive the pivot end of a finger 80.

Into a threaded hole in each carrier 81, I pass a set screw similar to that described in connection with Fig. 1 having a neck 44 which sets into a slot 145 in strip 132. By 120 turning these set screws carriers 81 may be moved in and out at will, each carrying with it a finger 80 and the marking means such as an awl 84 at the free end thereof.

For position determining means I may use 125 a bar 93 through which passes a screw shank 92 of a bolt which is turnable in a hole 91 through bar 124. I show a square head 90 for such bolt whereby it may be turned by a suitable key.

Each of my spacing links 94 connects a finger directly with the position determining means in a different relation therewith.

In this construction, my spacing links are 5 pivoted on the position determining means along the bar 93 in a line at right angles to the adjusting movement thereof and near their other ends on the different fingers at points which are at different distances from 10 the pivotal points thereof on the supporting means, that is the carriers 81.

In the construction shown in Figs. 9 and 10 the fingers are preferably pivoted on the carriers so that they will be nearly in line 15 with the in and out movement of the set screws. In the construction, where a flexible strip serves the purpose of carriers, it is also desirable that the direction of the fingers should not be at too great an angle with the 20 general direction of the lateral adjustment.

I prefer to embody my device in an invertible, bodily removable frame and I prefer that the carriers, fingers, links, set screws and all the other devices except the oppositely disposed awls should be between the 25 top and bottom of such frame. The awls should project beyond the top and bottom faces of the frame.

I claim:

30 1. In a device of the character described, the combination of supporting means, with a plurality of fingers each pivoted near one end thereon and each having a marking member near its other end, position determining means, and a plurality of spacing links which pivotally connect the fingers with the position determining means.

2. In a device of the character described, 40 the combination of supporting means, with a plurality of fingers each pivoted near one end on the supporting means, the pivots being in a curved line thereon, means whereby the shape of the line can be altered, each finger having a marking member near its 45 free end, position determining means, and a plurality of spacing links which pivotally connect the fingers in different relations with the position determining means.

3. In a device of the character described, 50 the combination of supporting means with a plurality of fingers each pivoted near one end on the supporting means, the pivots being in a line thereon, each finger having oppositely disposed marking means near its 55 free end, position determining means and a plurality of spacing links which pivotally connect the fingers in different relations with the position determining means.

4. In a device of the character described, 60 the combination of a frame, with a plurality of carriers arranged in a line, adjusting set screws carried by the frame for adjusting the positions of the carriers and changing the shape of the line, a plurality 65 of fingers each pivoted near one end to a

carrier and having a marking member near its other end, position determining means carried by the frame, and spacing links pivoted in different relations to the fingers and to the position determining means.

5. In a device of the character described, 70 the combination of an invertible frame, with a plurality of carriers inside thereof and laterally adjustable with reference thereto, a plurality of fingers each so pivoted near one end to a carrier as to be movable between the top and bottom of the frame and having near its other end oppositely disposed awls which project beyond the top and bottom of the frame, means for 80 laterally adjusting the carriers, longitudinal position determining means, and means including links which connect the fingers with the position determining means.

6. In a device of the character described, 85 the combination of an invertible frame, with a plurality of carriers arranged in a line inside thereof, adjusting set screws carried by the frame for adjusting the position of the carriers and changing the shape of the line, 90 a plurality of fingers each pivoted near one end to a carrier so as to be movable between the top and bottom of the frame and having near its other end a marking member, position determining means carried by 95 the frame, and spacing links pivoted in different relations to the fingers, and to the position determining means.

7. In a shoe upper marking machine, the combination of a reversible frame, with a 100 plurality of carriers inside thereof, a plurality of set screws each for laterally adjusting the position of a carrier with reference to the frame, a plurality of fingers each so pivoted near one end to a carrier as to be 105 movable between the top and bottom of the frame, oppositely disposed awls carried by the free end of each finger in such manner as to project beyond the top and bottom of the frame, longitudinal position determining means, and means, including links, 110 which connect the fingers in different relations with the position determining means.

8. In a shoe upper marking machine, the combination of a frame, with a plurality of 115 carriers separately laterally adjustable with reference thereto, a plurality of fingers each pivoted near one end to a carrier and having marking means near its free end, means for laterally adjusting the carriers and fingers 120 at a plurality of points, longitudinal position determining means proximate the carriers at one end, and links which connect the fingers in different relations with the position determining means.

9. In a shoe upper marking machine, the combination of a reversible frame, with a plurality of carriers inside thereof, a plurality of set screws each for separately laterally adjusting the position of a carrier 130

with reference to the frame, a plurality of fingers each so pivoted near one end to a carrier as to be movable between the top and bottom of the frame, oppositely disposed awls carried by the free end of each finger in such manner as to project beyond the top and bottom of the frame, longitudinal position determining means proximate

the carriers at one end, and links which connect the fingers in different relation with the position determining means whereby the spaces between the adjacent awls may be simultaneously altered.

In testimony whereof I hereto affix my signature.

JAMES J. CASEY.
